CARBON ROLL

Lester K. Fleischmann, Chicago, Ill.

Application November 23, 1954, Serial No. 470,682

6 Claims. (Cl. 197—126)

This invention relates to carbon rolls of the type adapted to be positioned on carbon holder mounting plates for use between adjacent strips of continuous-form stationery in a writing machine.

A number of carbon rolls have heretofore each been loosely supported upon a carbon holder between adjacent strips of continuous-form stationery with an unwound portion extending forwardly from each roll around the platen of a writing machine in registry with the stationery. The carbon holder is generally mounted for longitudinal movement upon a forms carrying device which in turn is secured to the rear of a writing machine so that the forms carrying device can move laterally with the carriage of the writing machine during a typing operation. The intermittent lateral movement of the forms carrying device has often caused the loosely supported carbon rolls to shift laterally out of alignment. Thus, when the unwound portions of the carbon being used are moved rearwardly for use between the next following form lengths of stationery, the carbons slide laterally out of alignment in following the misaligned carbon rolls. The typist must then realign the carbons before beginning the next typing operation. The present carbon roll structure eliminates this problem of lateral sliding in a carbon roll.

The primary object of the present invention is to provide a new and improved type of carbon roll and core.

Another object is to provide a hollow core of predetermined uniform width for a carbon roll so as to make a snug fit at its opposite edges with a mounting plate of a carbon holder.

A further object is to provide a carbon roll having a hollow core of uniform width, the core having a pair of oppositely disposed, transversely extending lines of weakening to determine precisely the two lines of fold in its lateral surface.

Still another object is to provide a new and improved method of forming a hollow core of predetermined uniform width for a carbon roll.

The invention is illustrated in the preferred embodiment in the accompanying drawings, in which:

Fig. 1 is a broken perspective view showing the hollow core and a portion of the carbon strip;

Fig. 2, a sectional view taken as indicated on line 2—2 of Fig. 1;

Fig. 3, a sectional view taken as indicated on line 3—3 of Fig. 4;

Fig. 4, a plan view of the paper sheet from which the hollow core is formed;

Fig. 5, a broken plan view partly in section showing the carbon roll in position upon a mounting plate of a carbon roll;

Fig. 6, a sectional view taken as indicated on line 6—6 of Fig. 5; and

Fig. 7, a sectional view taken as indicated on line 7—7 of Fig. 5.

In the embodiment illustrated, the carbon roll includes

2

a hollow, generally flat core member, generally designated 8, to which is secured one end of an elongated carbon strip 9 wound upon the core. The hollow core member is open at its opposite ends and has a fold along a line of weakening in each of its closed lateral edges 10 and 11, the edges being substantially parallel to form a core of uniform width. Since it is desired that each of the lateral edges makes a snug fit with a mounting plate 12 of the type shown in Figs. 5 and 6, the width of the core is made to conform to the particular mounting plate to be used.

As best seen in Fig. 4, the core 8 may be formed from a paper sheet, generally designated 13, of relatively durable material which is provided with a pair of parallel, transverse lines of weakening 14 and 15, respectively. The lines of weakening divide the sheet 13 into a pair of substantially congruent sheet sections 16 and 17, respectively, and a third sheet section 18 at the end of the sheet 13. It is clear that perforated lines, score lines or any other means for predetermined the position of fold in the sheet along a definite line could be used. The location of the lines of weakening 14 and 15 determine the width of the sheet sections 16 and 17 and the ultimate width of the core member 8, as can be seen in Fig. 2. The third sheet section 18 may also be provided with a line of weakening 19 defining one side of an end flap 20 having one of its faces covered with a pressure sensitive adhesive 21.

In forming the core 8, the sheet sections 16 and 18 at opposite ends of the sheet 13 are folded inwardly on lines of weakening 14 and 15 (sheet section 18 preferably on top) and secured together by adhesive 22. The resulting flat hollow core has an upper and a lower lateral surface, 8a and 8b, respectively, of identical configuration so that the core has a uniform width. The lines of weakening 14 and 15, of course, occupy the fold lines at the closed opposite edges of the core. Preferably the flap 20 at the free end of the sheet section 18 is left unsecured so that it may be folded back upon line of weakening 19. To attach the carbon strip 9, an end of the strip is inserted beneath flap 20, carbon side down, so that the back of the carbon strip 9 can be secured to the flap 20 by the adhesive 21. The desired length of carbon can then be wound upon the core 8. By attaching the extreme tip of the carbon strip 9 to the core 8, very little of the carbon is wasted. In addition, the carbon holder on which the carbon roll is mounted does not need any separate means for securing the carbon strip to the holder during a typing operation.

Since the core 8 is flexible, it may be placed upon a mandrel for the winding operation. Mandrels having variously shaped cross sections have been used. Some are circular; others are oblate or rectangular. Generally when the carbon roll is removed from the mandrel after a winding operation, the core 8 is held slightly oblate by the newly wound carbon. However, slight pressure exerted through the wound carbon strip 9 to the opposite lateral surfaces, 8a and 8b, of the core 8 causes the core once more to become flattened, the lines of weakening 14 and 15 assuring that the lines of fold in the core will not be changed from their original position. After the core is flattened, the carbon is creased slightly so it will better conform to the core; and the carbon roll will occupy less vertical space when placed between adjacent strips of continuous-form stationery.

A tab member 23 may be secured to an inner face of the hollow core, as by adhesive 24. It may be placed upon the sheet during the formation of the core 8, or it may be inserted into the hollow core after the core is formed. The tab member 23 is positioned so that an end portion extends outwardly of an end of the core 8. One face of this end portion is generally provided with

a spot of pressure sensitive adhesive 25 which is normally covered by the protective paper sheet 26 until it is desired to use the carbon roll.

To place the carbon roll upon the mounting plate 12, an open end of the core is located by grasping the tab member 23 which is secured to the interior of the hollow core. The hollow core 8 is then pulled over the mounting plate 12 to the desired position, as shown by either of the scales 27 on the mounting plate (Fig. 5). The protective paper 26 is then removed from the tab member 23 to permit the tab to be secured to the mounting plate by the adhesive 25. Generally the mounting plate is rotatable so that as much carbon as is desired can be unwound from the carbon roll.

The present carbon roll also makes it very easy to change carbons. When all of the carbon is unwound from the core, the tab member 23 is merely loosened from the mounting plate 12, and the core 8 is removed. Since the end of the carbon is attached to the core, the carbon strip 9 need not be touched by the typist.

Since the lateral edges 10 and 11 make a snug fit with the edges of the mounting plate 12, there is no tendency for the carbon roll to skew during a typing operation. In addition, the tab member 23, attached to the mounting plate by adhesive 25, also prevents the carbon roll from sliding laterally outwardly from between adjacent strips of continuous-form stationery, and correct alignment of stationery and carbon is assured at all times.

The foregoing detailed description is given for clearness of understanding only, and no unnecessary limitations should be understood therefrom, for some modifications will be obvious to those skilled in the art.

I claim:

1. A carbon roll adapted for use upon a mounting plate of a carbon holder between adjacent strips of continuous-form stationery, comprising: a hollow paper core open at its opposite ends and having a line of weakening in each of its oppositely disposed, closed, lateral edges, said lines of weakening being spaced apart to provide a core of predetermined width when folded on said lines so as to make a snug fit at its lateral edges with the mounting plate; and an elongated strip of carbon paper wound around said core, said strip being secured at one end to said core to retain the wound strip in lateral alignment.

2. A carbon roll adapted for use between adjacent strips of continuous-form stationery, comprising: a paper sheet having its end portions turned upon each other into

overlapping relationship and secured together to form a hollow core open at its opposite ends, the lateral surface of said core having a pair of parallel, transverse, oppositely disposed lines of weakening on which said lateral surface may be folded to form a pair of opposed core portions of the same width; and an elongated strip of carbon paper wound around said core, said strip being secured at one end to said core to retain the wound strip in lateral alignment.

3. A carbon roll as specified in claim 2, in which the end portions are secured together so as to provide on the outer lateral surface of the core an exposed unsecured free end of one of said end portions to which the strip of carbon is secured.

4. A carbon roll as specified in claim 2, in which a tab member is secured to an inner face of the hollow core, said tab member extending outwardly of one of the open ends of said hollow core and being provided with a pressure sensitive adhesive to aid in maintaining the carbon roll in proper position upon a mounting plate of a carbon holder.

5. A carbon roll assembly adapted for use in a carbon holder between adjacent strips of continuous form stationery, comprising: a hollow paper core open at its opposite ends and having a line of weakening in each of its oppositely disposed closed lateral edges, said lines of weakening being spaced apart to provide a core of predetermined width when folded on said lines; an elongated strip of carbon paper secured at one end to the core and wound thereupon to form a carbon roll; and a core mounting member positioned within said hollow core, said mounting member having opposite edge portions making a snug fit with said lines of weakening in the lateral edges of the core to restrict lateral movement of the core upon the mounting member during a typing operation.

6. A carbon roll assembly as specified in claim 5, in which a laterally extending indexing scale is provided on the mounting member so that a fresh carbon roll can be properly positioned on said mounting member when a used carbon roll is replaced.
